UNITED STATES PATENT OFFICE.

HENRY A. HILLS, OF GRAND RAPIDS, MICHIGAN.

DISTILLING AND PURIFYING APPARATUS FOR VOLATILE LIQUIDS.

1,372,880.

Specification of Letters Patent. Patented Mar. 29, 1921.

Application filed August 18, 1916. Serial No. 115,634.

To all whom it may concern:

Be it known that I, HENRY A. HILLS, a citizen of the United States, and a resident of the city of Grand Rapids, in the county 5 of Kent and State of Michigan, have invented certain new and useful Improvements in Distilling and Purifying Apparatus for Volatile Liquids; and I do hereby declare that the following is a full, clear, 10 and exact description of the same, reference being had to the accompanying drawings, and to the numerals of reference marked thereon, which form a part of this specification.

15 A considerable amount of cleaning fluid, such as gasolene, benzin, and the like, is used in cleaning establishments, and of course in using large quantities of the same it is necessary to recover and purify the 20 fluid so that the same may be used over again practically any number of times. Various types of apparatus have been designed and constructed for the purpose of purifying the fluid after use, involving distillation 25 and filtration of the same, but in general the apparatus has proved inefficient, and of course, unless a highly purified fluid is recovered, it is difficult to again use the fluid for delicate cleaning operations. There 30 have been various defects in the forms of apparatus used in the past. In the first place when the gasolene or other liquid contains a considerable amount of impurity foaming takes place which results in mechanically carrying over into the condenser 35 the impurities which rise to the surface of the liquid in the form of scum and which form the envelop around the bubbles in the froth or foam produced. Further these 40 prior forms of construction employed excessive quantities of steam and the water condensed from such steam was only partially removed from the condensed gasolene or other liquid.

45 One of the methods used in distilling the fluid is known as the dry process, that is, heating the fluid by means of steam coils, but this method, if used alone, is inefficient, due to the fact that steam at relatively high 50 pressure is necessary to secure the desired heat for the purpose, and also for the reason that certain foreign matter may render this treatment impractical because of foaming. Another method, known as the wet process 55 of distillation, is one wherein steam is blown through the fluid to distil the same,

passing over therewith to the condenser, and mechanisms are then necessary to separate the moisture or water from the condensed fluid. This method has heretofore been imperfect in results owing to the fact that the steam introduced merely lifted the froth formed at the surface of the fluid over into the condenser instead of breaking up or avoiding the formation of a froth. Further, it has heretofore involved a great waste of steam, and required a condenser of large capacity to condense the intermixed steam and volatilized fluid. In such machines, separation of all the water therefrom was 70 thought to be impractical.

This invention relates to an improved process and apparatus for purifying volatile cleaning fluids such as gasolene preferably with the aid of steam. I have found that 75 foaming may be avoided by agitating the fluid in the still sufficiently violently to prevent the accumulation of scum at the surface. For this purpose the fluid is preferably agitated in a vertical plane so that any 80 scum on the surface is drawn down and mixed with the body of the fluid. This agitation not only prevents foaming, but also by preventing the formation of a layer of scum aids the vaporization of the fluid by 85 continually presenting fresh surfaces of fluid to the vapor space thereabove.

It is an object, therefore, of this invention to provide a distilling and purifying process and apparatus for volatile fluids in 90 which foaming is eliminated.

A further object of the invention is to provide means for rapidly circulating the fluid in the still in a vertical plane to draw any scum on the surface down into the body 95 of the fluid and mix it therewith.

Another object of this invention to construct a distilling and purifying apparatus for volatile cleaning fluids embracing a still for heating the fluid by steam coils, and at 100 the same time violently agitating the same by direct application of steam to the fluid and subsequently condensing and passing the same through a separator, after which the fluid is passed through a water separator 105 or filter to remove remaining traces of moisture and other impurities possibly existing therein.

It is also an object of this invention to construct a distilling and purifying apparatus for fluids comprising a still, condensing means, separating mechanism to cause 110

separation of the moisture from the condensed distilled fluid, and an improved filtering device to remove remaining traces of moisture and impurities from the fluid.

5 It is also an object of this invention to construct a high efficiency still for volatile fluids constructed to utilize heating steam coils together with means for introducing a jet of steam directly into the fluid.

10 It is furthermore an important object of this invention to construct an apparatus utilizing both the dry and wet distilling systems and provided with an improved arrangement of separating and filtering devices to purify the distilled fluid.

15 It is finally an object of this invention to construct a simple, practical, and highly efficient distilling and purifying apparatus to receive a dirty and impure fluid and after 20 passage through the apparatus discharging the same as a clear and highly purified product.

25 The invention (in a preferred form) is illustrated in the drawings and hereinafter more fully described.

In the drawings:

Figure 1 is an elevation of an apparatus embodying the principles of my invention with certain of the elements of the system 30 shown in section.

Fig. 2 is a central vertical section through the filter with parts shown in elevation.

Fig. 3 is a sectional detail at one end of the filter.

35 Fig. 4 is an end view of the filter.

Fig. 5 is a side elevation of separator used in my apparatus.

Fig. 6 is a horizontal section taken therethrough with parts shown in elevation.

40 Fig. 7 is a longitudinal section on line 7-7 of Fig. 6.

Fig. 8 is a detail section taken on line 8-8 of Fig. 5.

45 Fig. 9 is a detail view of the steam inlet nozzle.

As shown in the drawings:

The reference numeral 1, indicates as a whole the still, which, as shown, consists of an upright cylinder provided with a conical 50 cover or end 2, into which an outlet pipe 3, is connected. Said cylinder 1, is provided with a sloping bottom 4, into which a drain or outlet pipe 5, is provided as well as a valved inlet pipe 5^a, near the upper end 55 thereof; said outlet pipe 5, being provided with a controlling valve 6. Mounted in the lower end of the still 1, is a steam coil 7, the inlet to which from a supply pipe 8, is controlled by a valve 9, and the outlet from 60 which is controlled by a valve 10. Also connected into the supply pipe 8, is a valve 11, controlling the flow through a nozzle 12, within the still, which is adapted to introduce steam directly into the fluid within the 65 still. Said nozzle 12, is shown in detail

in Fig. 9, and consists of a reducing coupling 12^a, into which a short length of pipe 12^b, of reduced diameter is connected and threaded onto the coupling 12^a. Inclosing said pipe 12^b, is a shell 12^c, which is provided with holes 12^d, therethrough at its inner or near end. The steam passing through this nozzle is adapted to draw fluid through the holes 12^d and project it forcibly and rapidly across the still. This fluid 70 strikes against the upper part of the inclined bottom 4 of the still and is thereby deflected upward so that such fluid is caused to circulate in a substantially vertical plane to draw down the scum on the surface of 80 the fluid and keep the latter thoroughly agitated. The particles of dirt suspended in the fluid strike the wall of the still above the nozzle and a large proportion thereof falls vertically downward along such wall 85 directly toward the outlet pipe 5. Mounted adjacent the still 1, is a condenser 13, comprising an upright cylinder open at its upper end, and at its lower end provided with a crown sheet or plate 14, beneath which is 90 a conical bottom 15. Connected sealingly through said crown sheet 14, are a series of upright tubes 16, which, at their upper ends, communicate through a plate 17, on which a conical top or cover 18, is riveted, brazed, or otherwise secured, and into which said pipe 3, from the still 1, is connected.

95 A distributing screen or plate 19, is mounted in said cover member 18, to distribute the contents flowing into the condenser 100 from the pipe 3, to the various tubes 16. An inlet pipe 20, is connected into the lower end of the cylinder 13, to admit a flow of cooling water to surround the condensing tubes 16, and an outlet pipe 21, is provided 105 at a convenient point at the upper end of said cylinder 13. An outlet pipe 22, is connected in the conical bottom 15, of the condenser to receive the condensed distillates, and said pipe leads into a T into which a 110 vent pipe 23, is connected, as well as a pipe 24, leading to a separator 25, designed to separate the moisture from the volatile fluid. Said separator 25, consists of a rectangular tank with a plurality of vertical longitudinal 115 baffles 26, therein, as clearly shown in Figs. 6 and 8, so arranged that the mixture of fluid entering into the tank through the inlet pipe 24, is constrained to take a tortuous passage around said baffle plates toward a fluid outlet pipe 27. The water outlet pipe 28 extends into the separator and downwardly close to the bottom thereof, as shown in Figs. 7 and 8, and leads outwardly 120 from said tank 25, at a slightly lower level than the outlet pipe 27. Connected on the side of the tank 25, is a glass gage 29, to indicate the position of the water level within the separator. As clearly shown, said outlet pipe 28, communicates into a T 30, hav- 125

ing a long upright vent pipe 31, connected therein, as well as a discharge pipe 32, the purpose of the vent pipe 31, being to prevent the contents of the tank 25, being siphoned 5 out through the discharge pipe 32.

Connected on the fluid outlet pipe 27, is a glass or sight chamber 33, and leading therefrom is a pipe 34, which communicates into a filter 35. Said filter is shown in de- 10 tail in Figs. 2 and 3, and, as shown, consists of a cylindrical casing or drum with detachable heads or ends 36 and 37, thereon. The head 37, has fitted thereto a ring or annulus 38, which fits over one end of the drum 35, 15 and said respective heads or ends 36 and 37, are clamped to one another on said drum 35, by means of long rods or bolts 39. Said annulus or ring 38, is provided with an inwardly convergent circular flange 40, and 20 mounted thereon is a filtering element consisting of inner and outer frusto-conical sleeves 41 and 42, respectively, with a layer of fabric therebetween, and another similar filtering element 43, is mounted on an in- 25 wardly convergent flange 44, formed on the head 37.

A stay rod or bolt 45, is threaded under the inner side of the head 37, and projects longitudinally within the drum 35, to afford 30 a support for the ends of said frusto-conical filter elements. Connected into the head 36, to communicate with the interior of the drum 35, is a sight glass chamber 46, provided with a discharge pet cock 47, and sim- 35ilarly connected into the annulus 38, is a sight glass receptacle 48, provided with a pet cock 49, said latter receptacle adapted to receive impurities passing through the first filter element 41—42, and checked in their 40 passage by the filter element 43. Another sight glass receptacle 50, provided with a pet cock 51, is connected through the head 37, of the drum, communicating with the interior of the filter element 43, so that by 45 means of said receptacles water or other impurities collected at the different stages in the filter may be detected and drained off from time to time, as desired. A discharge pipe 52, is connected through the head 37, 50 of the filter, from which the finally purified fluid is drawn off.

The operation is as follows:

The fluid for distillation and purification is introduced into the still or cylinder 1, 55 through the valved pipe 5^a, and steam is then admitted through the heating coil 7, by opening the valves 9 and 10. The utilization of the steam coil, as well as the direct introduction of steam through the nozzle 60 12, into the fluid for heating the same, effects an economical operation of the still, for the reason that by using a combination of the dry and wet method of distillation a much less volume of steam is used than 65 in either the dry or wet methods. The steam

coil is utilized to bring the contents of the still to the vaporization point, and after vaporization has been set up the wet steam is introduced through the nozzle 12, directly into the fluid to prevent the forma- 70 tion of froth and aid the distillation, and it is obvious that by proper manipulation of the valves controlling the respective steam supplies to the still, the most efficient operation for various conditions may be ob- 75 tained. The horizontal nozzle 12, serves also by the introduction of steam there- through, to set up a violent swirling mo- 80 tion to the contents of the still, this agita- tion contributing largely to the effectiveness 85 of operation as well as the efficiency or economy, as all the possible heating effect of the coils and jet is utilized. Further- more due to the construction of the steam inlet nozzle 12, pounding action within the 85 still due to the steam jet is obviated, said nozzle operating as an injector to draw the liquid inwardly through the apertures 12^a, and force the same with the jet of steam into the contents of the still. The prod- 90 ucts of distillation pass over and into the condenser and are condensed in the upright tubes and pass therefrom into the separa- 95 tor 25, which operates by gravity to sepa- rate the major portion of the water from the condensed fluid.

The separator 25, accomplishes its pur- 100 pose due to the different specific gravities of the water and volatile fluid, the water separating out and settling to the bottom of the tank during the tortuous passage of the contents of the separator toward the volatile fluid outlet pipe 27. Due to the fact that the water outlet pipe 28, extends to near the bottom of the interior of the 105 tank 25, a certain amount of water is al- ways trapped therein and may be drained off through the T 30, and outlet pipe 32, at a lower level than the oil within the tank due to the difference in specific grav- 110 ies of the water and oil. The vent pipe 31, prevents a siphon effect taking place through the outlet pipe 28, and discharge pipe 32, for the water. The position of the outlet pipe 27, for the volatile fluid is such 115 with respect to the position or height of the water outlet, that regardless of the quantity of water within the tank 25, the fluid rising to the outlet pipe 27, will always flow out- wardly therethrough and has no tendency 120 to set up a flow of the fluid outwardly through the water outlet pipe 28, and of course the outflow of water is automatic, only occurring when the quantity in the tank 25, reaches an amount sufficient to 125 cause a rise in the level of the water to set up a flow outwardly through the discharge pipe therefor.

The separated volatile fluid leaving by the outlet pipe 27, enters the sight glass 130

chamber 33, and from there passes into the filter 35, wherein any traces of suspended moisture or other impurities are filtered out, and the volatile fluid leaving by the 5 pipe 52, is entirely pure and clear. The vent pipe 23, connected into the T which connects the pipes 22 and 24, from the condenser into the separator, acts to prevent an augmentation or lowering of pressure 10 within the condenser or separator beyond atmospheric.

I am aware that various details of construction may be varied through a wide range without departing from the principles of this invention, and I therefore do not purpose limiting the patent granted otherwise than necessitated by the prior art.

I claim as my invention:

1. In a still having a sloping bottom, a 20 vapor outlet at the top and a liquid inlet, the combination of a nozzle adjacent the bottom of the still having its discharge opening directed against said bottom, said nozzle having a sleeve surrounding and 25 spaced therefrom to provide an annular chamber around the nozzle, and an opening

at the rear end of said chamber for supplying fluid by suction through the chamber simultaneously with the exhaust from the nozzle.

2. In an apparatus of the class described, a still, a steam heating coil therein, a discharge orifice adjacent one side of the vertical wall of the still, a bottom sloping downwardly from the opposite wall of the 35 still toward said orifice and an aspirating nozzle, said nozzle being supplied with steam from the same source as the heating coil and positioned substantially vertically above the discharge orifice and directed toward the sloping bottom of the still for supplying steam under pressure into the still and also maintaining a circulation of the liquid therein.

In testimony whereof I have hereunto 45 subscribed my name in the presence of two subscribing witnesses.

HENRY A. HILLS.
